UNITED STATES PATENT OFFICE.

HENRI H. HENDERSON, OF STOCKTON, CALIFORNIA.

AIR-LIFT AND AIR-DRIVEN ROTARY PUMP.

Application filed May 28, 1923. Serial No. 641,918.

To all whom it may concern:

Be it known that I, HENRI H. HENDERSON, a citizen of the United States, residing at Stockton, county of San Joaquin, 5 State of California, have invented certain new and useful Improvements in Air-Lift and Air-Driven Rotary Pumps; and I do declare the following to be a full, clear, and exact description of the same, reference being had to the accompanying drawings, and to the characters of reference marked thereon, which form a part of this application.

This invention relates to improvements in pumps, for water and the like, of that general type adapted to set vertically in a well casing, and commonly designated as turbine or rotary pumps.

The principal object of my invention is to produce a pump of this character to be 20 driven by compressed air, and so constructed and arranged that the exhaust air is then utilized as an air-lift or boost for the water.

I appreciate of course that in itself, to drive a pump by compressed air is not novel, 25 and neither is the utilization of air to lift the water; but as far as I am aware, no pumps for submerged service have been constructed which are driven by compressed air applied at a point adjacent the pump-vanes 30 or rotor, and which then use the same air, after it has served its driving purposes, for aiding in the lift of the water.

A pump constructed according to my invention will, I believe, be inexpensive to 35 manufacture and operate, and extremely long lived, since there is but one moving member, and two opposed bearings for the same, which may easily be of a character which will give long and satisfactory service without attention or renewal.

These objects I accomplish by means of such structure and relative arrangement of parts as will fully appear by a perusal of the following specification and claims.

45 In the drawings similar characters of reference indicate corresponding parts in the several views:

Fig. 1 is a vertical elevation of the pump as installed in a well casing, partly in section.

Fig. 2 is a cross section on the line 2—2 of Fig. 1.

Fig. 3 is a fragmentary detached view of a portion of the rotor.

55 Fig. 4 shows a modification of the rotor. Referring now more particularly to the

characters of reference on the drawings, the numeral 1 denotes a circular casing, provided on its inner periphery with vertically disposed vanes 2 formed as ratchet-shaped teeth extending substantially from top to bottom of the casing, at which points the teeth are shrouded, as shown by the flanges 3.

Arms 4 extend upwardly from the top of the casing, at a suitable angle toward each other, and terminate at their upper end in a hub or boss 5 to receive the upper end of a hollow shaft 6 therein. Roller or similar bearings 7 are provided for the shaft in the upper portion of the member 5, while in the lower portion thereof is a stuffing box structure 8 of suitable form.

Secured on the boss 5 is a removable cap 9, into which the lower end of an air supply pipe 10 is adapted to be screwed, and which supports the casing and parts mounted therein.

The arms 4 are preferably triangular in shape, with the apex or edge inwardly or downwardly, so as to offer little resistance to the passage of the water therewith. The lower ends of said arms have feet 11 which rest on enlarged pads 12 on the casing and are removably secured thereto. These pads 13 preferably extend the full height of the casing as ribs having an easy fit in the well casing 14, serving as abutments for one or more stops 15 of a suitable character mounted in the well casing, and preventing rotation of the casing 1 while allowing it freedom of vertical movement.

Extending downwardly from the lower ends of the pads or ribs 12 are arms 16, converging toward each other and formed at their lower ends with a boss 17 serving as a journal and support for the lower end of the shaft 6, a suitable form of thrust bearing as at 18 being placed between the shaft and boss or bearing member. A stuffing box 19 is provided on the bearing member 17 above the thrust bearing. These arms 16 are also triangular in shape, with the apex along the outer edges thereof, and the boss 17 is preferably pointed on its lower end, to reduce resistance to the flow of water therewith. A small bore 6^a leads from the main bore of the shaft 6 to the lower end thereof, which is spaced from the bottom of the bore of the boss 17.

Preferably formed integral with the shaft between the top and bottom of the casing 1

are horizontal and suitably pitched impeller-vanes 20, arranged in vertically disposed sets of a desired number, these vanes being similar in form and pitch relative to the shaft 6, as are the blades of a fan or the usual screw propeller.

The vanes of the different sets are vertically aligned with each other, and the outer ends of the aligned vanes are connected to, and preferably formed integral with, hollow vertical arms 21, extending from top to bottom of the casing 1, and having a close running fit therein and with the teeth 2 except that pockets or vertical grooves 22 are provided in their outer peripheries intermediate their vertical end edges.

These arms are hollow as at 21^a from top to bottom but plugged at their ends, the hollow areas communicating with the interior of the shaft 6 by means of passages 23 through the vanes 20. Bored from the arm-pockets 22 to the hollow interior of the arms is a plurality of air-blast holes 24, disposed so that air issuing therefrom will impinge directly against the substantially radial faces of the adjacent teeth 2, the pockets being of such peripheral extent relative to the pitch or width of the teeth that at least one whole tooth will be within the pocket area.

The forward or leading edges of the arms 21 are concavely curved as shown at 25, so as to aid in sweeping the water onto the vanes.

In operation, with the pump lowered into the water in the well casing, the admission of air at a suitable pressure into the shaft 6 from the pipe 10 will of course pass into the arm-passages 21^a, and from thence out through the nozzles or jet openings 24, with a velocity depending of course on the pressure of the air.

The jets of air, striking the casing teeth or vanes 2, causes the arms 21, together of course with the blades or vanes 20 and shaft 6, to rotate, since the casing 1 is held against rotation in the stationary well casing, as previously described.

The pitch of the impeller blades is of course so disposed relative to the necessary direction of rotation of the shaft that the water in which the pump is submerged will be forced upwardly. At the same time, the air, after issuing from the nozzles and exerting its force to rotate the impeller, is with such rotation released from the pockets 22 formed between the vanes 2 and the arms 21, and mingles with the water passing up inside the casing 1.

Since the air has considerable pressure, and in any event tends to rise to the top of the water, it acts to boost or help lift the latter, functioning in the manner already recognized and made use of in the pumping art or profession.

By reason of the close fit of the arms 21 with the casing vanes, and the shrouding of the upper and lower ends of the latter, but a very slight percentage of the air issuing from the nozzles will escape without doing effective work in rotating the impeller unit.

The small bore 6^a in the lower end of the shaft 6 enables the air pressure to pass below the shaft, when pressing upwardly thereagainst, it acts as a cushion for the shaft, relieves the strain on the bearing 18, and reduces friction.

If desired, the rotor arms 21^a shown in Fig. 4 may be made with a compounding or auxiliary air drive feature, this consisting of an additional vertical groove or pocket 26 beyond the pocket 22^a having the jets therein. In this manner, with the movement of the arms past the vanes 2, the air confined between said vanes and the arms, instead of immediately escaping into the casing, will first pass into the pockets 26, aiding in the rotating of the arms, though of course having a lesser pressure than the air issuing from the jets.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A pump for submerged service comprising a stationary and open ended casing, an impeller structure turnably mounted therein, and means for rotating the impeller structure by compressed air applied between said structure and the casing from top to bottom thereof.

2. A pump comprising a stationary and open ended casing, an impeller structure turnably mounted therein, vertical fixed vanes in the casing, and means for rotating the impeller structure by compressed air applied against the vanes from said structure.

3. A pump for submerged service comprising a stationary and open ended casing, an impeller structure turnably mounted therein, vertical vanes in the casing, air-jet means provided with the impeller structure and facing said vanes, and means for supplying air under pressure to said jets.

4. A pump for submerged service comprising a stationary and open ended casing, an impeller structure turnably mounted therein, vertical vanes in the casing, air-jet means provided with the impeller structure

and facing said vanes, a hollow shaft formed as the axis of the impeller structure, an air pipe connected to communicate with the shaft, and passage means from the shaft 5 to the jets.

5. A pump for submerged service comprising a stationary and open ended casing, an impeller structure turnably mounted therein, vertical vanes in the casing, air-jet means provided with the impeller structure and facing said vanes, a hollow shaft formed as the axis of the impeller structure, passage means from the shaft to the jets, and an air pipe secured to the upper end of 10 the casing and supporting the same, the upper end of the hollow shaft communicating with the air pipe.

6. A pump for submerged service comprising a stationary open ended casing structure, a shaft turnably mounted centrally thereof and supported thereby, horizontally pitched impeller blades projecting outwardly from the shafts, hollow arms provided with horizontally disposed air jet means positioned at the outer ends of the blades, vertical vanes in the casing toward which the jets face, the arms having a running fit with the vanes, and means for feeding air under pressure to the jets.

30 7. A pump for submerged service comprising a stationary open ended casing structure, a shaft turnably mounted centrally thereof and supported thereby, horizontally pitched impeller blades projecting outwardly from the shaft, hollow arms provided with horizontally disposed air jet means positioned at the outer end of the blades, vertical vanes in the casing toward which the jets face, the arms having a running fit with the vanes, the blades and shaft being hollow and communicating with the interior of the arms; means being provided for feeding air under pressure to the shaft.

45 8. A pump for submerged service comprising a stationary open ended casing structure, a shaft turnably mounted centrally thereof and supported thereby, a plurality of vertically spaced rows of horizontally pitched impeller blades arranged in 50 vertical alignment, hollow arms connecting the vertically aligned blades at their outer ends, air jet means leading from one of

the vertical faces of each of the arms, vertical vanes in the casing toward which the jets face, the arms having a running fit with 55 the vanes, and means for feeding air under pressure to all the arms and jets simultaneously.

9. A pump for submerged service comprising a stationary open ended casing structure, a shaft turnably mounted centrally thereof and supported thereby, horizontally pitched impeller blades projecting outwardly from the shaft, hollow arms at 60 the outer ends of the blades, vertical vanes 65 in the casing, the arms having a running fit with the vanes except for vertical grooves intermediate their vertical edges which form pockets with the vanes, horizontal air jet means in the arms opening into the pockets and facing the vanes, and means for 70 feeding air under pressure to the jets.

10. A pump for submerged surface comprising an open ended casing having vertical vanes around its inner periphery, an impeller structure turnably mounted in the casing, vertical arms provided with said structure and positioned adjacent the casing-vanes, said arms having spaced and vertical grooves on their peripheral faces, and 75 jets projecting from the forward ones of the pockets relative to the direction of imparted rotation and facing the vanes.

11. A pump for submerged surface comprising an open ended casing having vertical vanes around its inner periphery, an impeller structure turnably mounted in the casing, vertical arms provided with said structure and positioned adjacent the casing-vanes, air jet means in the arms acting 80 against the vanes, and means whereby the air is caused to exert a compound action on the arms before being exhausted.

12. A pump comprising a stationary and open ended casing, an impeller structure 85 turnably mounted therein, means for rotating the impeller by compressed air applied between the casing and impeller, and means whereby the air will then be discharged into the liquid in that zone thereof being acted 90 on by the impeller.

In testimony whereof I affix my signature.

HENRI H. HENDERSON.
